Inventor:

Archer L. Knapp,

By *Miller T. Hobbs*

Attorney.

UNITED STATES PATENT OFFICE.

ARCHER L. KNAPP, OF DETROIT, MICHIGAN, ASSIGNOR TO PACKARD MOTOR CAR COMPANY, OF DETROIT, MICHIGAN, A CORPORATION OF MICHIGAN.

FASTENER.

Application filed April 30, 1923. Serial No. 635,469.

This invention relates to motor vehicles, and particularly to curtains such as are used thereon. It has for its object to provide a curtain so constructed that the rattle which is common in such equipment shall be prevented, without in any way impairing the efficiency of the curtain, or the facility with which it may be used, and without affecting the appearance of the vehicle to which it may be attached.

Other objects and structural features of the invention will appear from the following description taken in connection with the drawing, which forms a part of this specification, and in which:

Fig. 1 is a perspective view of part of a motor vehicle provided with curtains constructed in accordance with the invention;

Fig. 2 is an enlarged view, partially in elevation and partially in section, through a pair of curtains such as are illustrated in Fig. 1, the curtains being separated;

Fig. 3 is a view similar to Fig. 2, the curtains being fastened together;

Fig. 4 is a perspective view of a portion of the inside of one of the curtains illustrated in Fig. 1, illustrating an application of the invention;

Fig. 5 is a section through a pair of unfastened curtains equipped with a different form of the invention;

Fig. 6 is a view similar to Fig. 5, showing the members of the curtain fastening means in contact with each other, and

Fig. 7 is a view through a curtain provided with a fastener of slightly different form.

As is well known, the curtains of motor vehicles are frequently equipped with snap fasteners by means of which various sections of the curtains are secured to each other, or to the body or top frame of the vehicle. It frequently happens that the vehicle is driven with only a portion of its curtains up, or with one or more of them unfastened. Under such circumstances a persistent and annoying rattle is produced, while the car is in motion, by the striking together of the two co-operating parts of the fastener, which are suspended in juxtaposition but are not connected together.

This invention provides curtains having means to completely deaden the aforementioned rattle, which means does not detract

from the appearance of the installed curtains, or may indeed even add to the appearance thereof, and which is relatively inexpensive.

In Fig. 1 there is shown at 10 a motor vehicle having a body 11 and a top 12 between which are disposed side curtains 13 and 14 in the usual manner. The curtains 13 and 14 are of any suitable material, such as the fabric usually employed for this purpose, and are provided with fasteners 16 by means of which they are attached to the vehicle and to each other. As illustrated these fasteners are of the well known glove or snap variety, but it is to be understood that the invention is not limited in its application to such fasteners, but is applicable to other fasteners as well.

As best shown in Figs. 5 and 6, the fastener is composed of two portions, a male member 17 preferably hollow as shown and a cooperating female member 18, adapted to be sprung into detachable engagement therewith, in the well known manner. These members may be, and usually are metallic stampings. The male member 17 is composed of two parts, a stud portion 19, forming an annular, resilient shoulder 21, and a post portion 22. These parts are rigidly secured together in any suitable manner, as by crimping. The post portion 22 is projected through a hole 23, cut in the curtain 14, and is secured thereto by riveting over, as at 24, so that the portion of the curtain which surrounds the hole 23 is clamped between the two parts of the male member 17.

The female member 18 of the fastener comprises a cap or button 26, to which is secured a depending, annular, inturned flange part 27, adapted to surround the shoulder 21 of the male member 17. The flange 27 is provided on its interior with a split ring 28 to resiliently engage the shoulder 21 and spring or snap thereon to secure the members together. The female member 18 is seated in a suitable hole 29 in the curtain 13, which is clamped between the cap and the flanged member in the usual manner.

It will be understood that the snap fastener so far described is of the usual well known construction. When the members 17 and 18 of such a device are unfastened, vibration of the curtains 13 and 14, such as would be occasioned by motion of the ve-

hicle, causes them to strike together continuously, producing the rattling sound above referred to.

To overcome this objection, this invention contemplates the use of cushioning means between the co-operating members of the fastener. In the form of the invention shown in Figs. 2, 3 and 4, a flap or pad 31 of suitable sound deadening material such as fabric is sewed to the curtain above one of the fastening members and depends in such position as to cover one of these members. In this manner when the curtains are unfastened the flap 31 will lie between the flange 27 of the female member and the shoulder 21 of the male member so as to prevent contact between them, and thus prevent the rattling sound above referred to. When it is desired to fasten the curtains together the flap 31 is turned upwardly to a position such as that illustrated in Fig. 3, when the co-operating parts of the fastener may be pushed into engagement in the usual manner. The flap 31 is preferably somewhat thinner and more flexible than the material composing the curtains 13 and 14, so that it may be readily folded and will be supported between the curtains in an upstanding position, as illustrated in Fig. 3. By concealing the fastening member the flap 31 also enhances the neat appearance of the curtains.

In Figs 5 and 6 is illustrated another form of the invention, which provides a plug 33, of suitable resilient or sound deadening material, such as rubber, preferably placed within the hollow male portion 17 of the fastener, projecting slightly therefrom so as to receive and cushion the tapping of the female member 18 thereagainst. The plug 33 may be secured in the male portion in any suitable manner. As illustrated in Fig. 5, it is held in place by frictional engagement, but it is understood that it may be cemented or otherwise secured in position. The plug 33 extends above the stud and radially as far as the crest of the shoulder 21, to insure cushioning of the contacting member 18, and the central portion of its face is preferably cut away, as shown at 34, to prevent interference with the central portion of the button 26.

It will be seen that as the curtains 13 and 14 vibrate from the vehicle motion, or from other causes, while the fasteners are unfastened, the parts of the fastener will repeatedly assume the positions shown in Figs. 5 and 6 respectively. By reference to Fig. 6 however, it will be seen that when the motion of the curtains tends to bring the fastening members 17 and 18 together, the plug or bumper 33 will strike against the

other member of the fastener, thus preventing the contact of metallic parts and the ensuing rattle. The plug 33 is, however, readily compressible, and is easily squeezed within the ring 28 when it is desired to snap the members 17 and 18 into engagement.

In Fig. 7 is illustrated the male member 70 of a fastener of the type in which the stud portion 19 and the post portion 22 are clamped together on the curtain 14 by means of a rivet 36. In this structure the head 77 of the rivet 36 is sunk into the plug 33 thus securing it, the stud portion 19, and the post portion 22 together. It will be evident that either of the members of the fastener may be secured to other objects than curtains; for example the male member may be secured to the body or to the top bow of an automobile. 80

It will be understood that various forms of the invention other than those described above may be used without departing from the spirit or scope of the invention. 85

What is claimed is:

1. The combination with a fastener comprising a hollow male member and a female member adapted to co-operate therewith, of a resilient plug secured in the hollow male member and projecting axially and radially therefrom to cushion the female member. 90

2. In a fastener comprising a hollow male member and a female member adapted to co-operate therewith, a resilient plug secured in one of the members and projecting axially and radially therefrom to cushion the contact of the other member. 95

3. A fastener comprising a male member having a stud portion and a post portion, a female member to co-operate with the male member, a resilient plug mounted in the stud portion and means in the post portion for securing the plug in position. 100

4. A fastener comprising a male member having a hollow stud portion and a hollow post portion, a female member to co-operate with the male member, a resilient plug mounted in the stud portion and means mounted axially in the post portion for securing the post portion, stud portion and plug together. 105

5. A fastener comprising a male member having a shouldered recessed stud portion and a hollow post portion, a female member to co-operate with the male member, a resilient plug in the recessed stud portion extending axially and radially therefrom and means mounted in the post portion for binding the post portion, stud portion and plug together. 115 120

In testimony whereof I affix my signature.

ARCHER L. KNAPP.
